(57) **CLAIM**

The ornamental design for a modular satellite equipment station, as shown and described.

DESCRIPTION

FIG. 1 is a first perspective view of a modular satellite equipment station showing our new design;

FIG. 2 is a second perspective view of a modular satellite equipment station shown in FIG. 1;

FIG. 3 is a top view of the modular satellite equipment station shown in FIG. 1;

FIG. 4 is a bottom view of the modular satellite equipment station shown in FIG. 1;

FIG. 5 is a front view of the modular satellite equipment station shown in FIG. 1;

FIG. 6 is a rear view of the modular satellite equipment station shown in FIG. 1;

FIG. 7 is a left side view of the modular satellite equipment station shown in FIG. 1; and,

FIG. 8 is a right side view of the modular satellite equipment station shown in FIG. 1.

The broken lines showing the inner and outer walls, floor, roof, and shelves of the modular satellite equipment station are included to show features that form no part of the claimed design.
